MEANS FOR POSITIONING AND REGISTERING PRINTING MEMBERS ON CYLINDERS OF ROTARY PRESSES

Edward Leeburg, Roselle, N. J.

Application November 3, 1950, Serial No. 193,878

3 Claims. (Cl. 101—174)

1

My invention relates to rotary printing presses and especially to multi-color rotary printing machines. More particularly the invention relates to gage attachments to be applied to rotary printing cylinders for registering and properly positioning thereon printing members such as flexible printing bands or pads, stereotype plates and the like.

While this invention has other uses, it is especially well adapted for use in connection with the mechanism disclosed in my other application for Means For Tightening and Adjusting Flexible Bands On Printing Cylinders of Rotary Presses, filed simultaneously herewith and bearing Serial No. 193,877, now abandoned and replaced by Serial No. 332,642, filed January 22, 1953.

In multi-color printing presses the web of paper passes from one printing cylinder to the next to receive the different colored impressions from the printing bands or plates on the cylinders, and it is of extreme importance that the different impressions be in registration.

When such presses use flexible printing bands or plates, it requires a great deal of time and skill to properly position them on the cylinders so as to obtain the proper alinement and registration. Expensive telescopic alining devices have been used in getting the printing bands on the several cylinders in line in the direction of movement of the paper, and other complicated means have been employed to get the proper registration of the several color impressions or printings.

The principal object of the invention is to provide a gage device of the above indicated character which may be mounted on the several printing cylinders successively and used to properly position the flexible printing bands lengthwise of the cylinders so that the bands on all of the cylinders will be in line, to properly position the bands circumferentially of the cylinders so the different imprints will be in registration, and to so position the bands that the horizontal lines of printing indicia will be at right angles to the edges of the paper sheet.

Another object of the invention is to provide a device of this character which is of simple and practical construction, which will save much time in correctly positioning the printing bands or plates on the several cylinders of the press and which may be effectively used by relatively unskilled workers.

With the above and other objects and advantages in view, the invention resides in the novel combinations and arrangements of parts and the

2

novel features of construction hereinafter described and claimed, and illustrated in the accompanying drawings which show the present preferred embodiment of the invention.

5 In the drawings:

Fig. 1 is an end elevation of a rotary printing cylinder showing the gage device applied thereto, the shaft of the cylinder being in section;

Fig. 2 is a top plan view, parts being broken away;

Fig. 3 is a detail section on line 3—3 of Fig. 1, parts being broken away;

Fig. 4 is an outside view of the printing cylinder with a portion broken away, and showing holes for properly positioning the gage device thereon;

Fig. 5 is a detail section taken on line 5—5 of Fig. 2; and

Fig. 6 is a detail section taken on line 6—6 of Fig. 1.

10 Referring more in detail to the drawings, the numeral 10 denotes one of the several similar printing cylinders of a rotary printing press. Such cylinders are usually hollow and are made in various lengths and diameters. The cylinder is suitably fixed to a shaft 11 journaled in bearings 12 on the frame 13 of the press. The cylinder has flat end walls connected by a cylindrical side wall 14 in which is formed the usual gap or slot 15 to receive both ends of a flexible printing pad or band 16. While these printing bands or members 16 are of various constructions and various means may be provided for adjusting and tightening them on the cylinders, I have shown in the drawings the same structures that are disclosed in my above mentioned application, and I will now briefly describe them.

15 The flexible printing member 16 has a base 17 of canvas or the like and a thick body portion 18 of rubber, rubber-like composition or plastic material on which are formed raised printing indicia 19 the latter forming the printing surface. Within the cylinder opposite the slot 15 is a winding reel, the reduced ends 20 of which are shown in Figs. 1 and 2. The fabric ends of the band 16 are fastened to the reel so that when the latter is rotated in one direction both ends of the band will be pulled into the slot to tighten the band on the cylinder. The reel is mounted both for rotation and for the angling of its axis with respect to the axis of the cylinder so that any skew in the band, when it is drawn against the surface of the cylinder, may be removed. The reel has near its extremities reduced journal portions 25 which rotate in bearing openings eccentrically positioned in circular discs 26. The latter are

in turn rotatable in aligned circular openings 24 in the end walls of the cylinder 10. The eccentric bearing disks 25 carry radial arms 36 with arcuate slots 37 to receive clamping screws 38 for clamping the arms against the cylinder end walls, thus locking the eccentric bearings 25 in adjusted positions. The reel may be rotated by inserting a wrench or turning tool in either hexagonal socket 30 formed in the projecting ends 29 of the reel. The reel is locked in adjusted position by detachable radial arms 32 having hexagonal openings 31 to receive the similarly shaped projections 29 on the reel. The outer ends of the arms 32 have arcuate slots 34 to receive screws 35 which clamp them against the cylinder end walls. It will be seen that when the arms 32 are not tightly clamped and the screws 38 are loose, the arms 36 may be moved to cause the eccentric bearing disks 25 to be turned to change the angular relation of the reel axis to the cylinder axis, and hence the printing band may be squared on the cylinder and any skew in it removed so that all portions of the band around the cylinder may be drawn tight against its surface.

My improved gage device comprises a gage bar or rod 40 longer than the cylinder 10 along which it is to be temporarily supported by two supports or standards 41. The rod is shown as being cylindrical and it is removably and adjustably mounted in openings in the supports 41 by means of set screws 42. The supports 41 have elongated bases 43 which extend circumferentially of the cylinder and which are curved to conform to the curvature of the cylinder as seen in Fig. 5. Since the device is to be applied to the different cylinders of the press in succession in alining and registering the different printing bands or plates, I provide means for positioning and securing it in exactly the same position on each cylinder. That is accomplished by forming on the curved bottoms of the bases 43 near one end integral locating pins or dowels 44 of a size to fit holes or openings 45 formed in the surface of each cylinder near its ends, as seen in Fig. 4. These holes 45 are positioned at exactly the same distance from a longitudinal edge of the slot 15 in each cylinder or from some gage mark on the cylinder. The supports or standards when thus located, are fastened by machine screws or bolts 46 which pass through openings 47 in the enlarged bases and into threaded holes 48 formed in the cylinder surfaces in circumferentially spaced relation to the locating holes 45.

The gage rod supports two gage members 49 and 50. The gage element 49 is used to position the printing bands on all of the cylinders in alinement in the direction of movement of the paper. It is preferably in the form of a crescent shaped plate disposed vertically adjacent one end of the cylinder and adjustably carried by the rod 40. The lower edge 51 of the gage plate 49 conforms to the curvature of the cylinder and preferably extends a little less than half-way around the latter. The plate is riveted or otherwise secured as at 52 to a lug or arm 53 projecting from the cross portion of an inverted U-shaped slide 54 mounted on the gage rod. The two arms 55 and 56 of the U-shaped slide are apertured to slidably receive the rod 40, the arm 56 being on the outer side of the adjacent standard 41 from which one end of the rod projects a suitable distance. That permits the gage plate to be adjusted close to the adjacent end of the cylinder for very wide printing bands and at the same time the gage plate is rigidly supported. While a suitable gage

mark may be on each printing member to coact with the gage plate, I find it satisfactory to abut the adjacent edge of the raised printing surface 19 against the gage plate to properly position the band lengthwise of the cylinder. When that has been done the slide 54 is locked to the rod by a set screw 57 threaded into the arm 56. When the gage plate is thus set on the first printing cylinder the device may be applied to the other cylinders in succession and the bands on those cylinders when abutted against the gage plate will cause all of the printing bands to be in alinement. On the gage rod 40 is a graduated scale 58 in any suitable linear units to cooperate with the edge of the slide arm 55 so that a particular adjustment of the gage plate may be noted.

The gage element or member 50 is used in squaring the printing band or plate on the cylinder and positioning the lines of printing indicia on the printing surface 19 at right angles to the edges of the paper. The gage 50 is in the nature of a straight edge consisting of a straight flat bar having a length substantially that of the cylinder and preferably having a beveled outer edge. It is hung from the rod 40 for vertical swinging movement so that it may contact with the surface 19. As shown in Fig. 2 the gage bar 50 has fixed to it near its ends two arms 59 which are apertured to receive the rod 40 and which are positioned to contact with the flat opposing faces of the supports or standards 41 so that the gage bar is prevented from shifting longitudinally but can swing vertically. To prevent the gage bar from interfering with the adjustment of the gage plate, the latter has a portion of its inner or lower edge cut away as at 60. Since the axis of the rod 40 is parallel with the axis of the cylinder and the arms 59 are of equal length, the beveled edge of the bar 50 will indicate the proper positioning of the horizontal rows of printing indicia on the surface 19. If such rows are not in line with the straight edge of the bar 50 one or the other of the eccentric bearing discs 25 may be adjusted to shift the printing band on the cylinder so that the rows of indicia are at right angles to the edges of the paper web.

From the foregoing, taken in connection with the accompanying drawing, it will be seen that novel and advantageous provision has been made for carrying out the objects of the invention, and while preferences have been disclosed, attention is invited to the possibility of making variations within the scope of the invention as claimed.

I claim:

1. A gage device for positioning a printing member on a rotary cylinder of a press comprising a pair of standards having means at their lower ends for removably mounting them on the curved surface of a printing cylinder adjacent the ends of the latter, a gage rod extending between and supported by said standards parallel to the axis of the cylinder, one end of said rod projecting outwardly beyond one of said standards, a U-shaped slide having arms apertured to receive and slide on said rod, said slide straddling said one of said standards to position one of said arms on the projecting end of said rod, a vertically disposed gage plate fixed to said slide and having its lower edge curved to conform to the curvature of a printing cylinder to coact with a printing member thereon, means for fastening said slide in an adjusted position on said rod, a gage bar for disposition longitudinally of a printing cylinder and having a straight edge to coact with a print-

ing band thereon, and a pair of suspending arms for said bar pivotally hung from said rod, the last mentioned arms contacting the opposed sides of said standards to prevent longitudinal movement of said bar, the lower portion of said gage plate being cut away to clear the rod and bar.

2. In a gage attachment to be successively applied to the different printing cylinders of a rotary press to align and register flexible printing bands on the cylinders, the combination with a printing cylinder having a smooth cylindrical surface with a longitudinal slot extending from end to end to receive the ends of a flexible printing band encircling the cylinder, the said cylindrical surface having gage-locating holes near the ends of the cylinder and equally spaced from said slot, said cylindrical surface also having screw threaded holes spaced circumferentially from said gage-locating holes, of a gage device for removable attachment to the cylinder and comprising a gage rod disposed longitudinally of the cylinder, standards for supporting said rod parallel with the axis of the cylinder, said standards having elongated bases extending circumferentially of the cylinder with bottom faces longitudinally curved to conform to and contact with said cylindrical surface, locating pins projecting from said bottom faces adjacent one of the ends of said bases and disposed in said gage-locating holes, the other ends of said bases having holes to register with said screw threaded holes, headed screws in said registering holes to fasten said standards to the cylinder, said rod being longer than the cylinder and having one end projecting outwardly beyond one of said standards, a U-shaped slide having arms apertured to receive and slide on said rod, said slide straddling said one of said standards to position one of said arms on the projecting end of said rod, a vertically disposed gage plate fixed to said slide and having its lower edge curved to conform to the curvature of the cylinder and to coact with a printing band thereon, means for fixing said slide in an adjusted position on said rod, a gage bar disposed longitudinally of the cylinder and having a straight edge to coact with a printing band thereon, and a pair of suspending arms for said bar pivotally hung from said rod and disposed for contact with the opposite sides of said standards to prevent longitudinal movement of said bar, the lower portion of said gage plate being cut away to clear the rod and bar.

3. In a gage attachment to be successively applied to the different printing cylinders of a rotary press to align and register flexible printing bands on the cylinders, the combination with a printing cylinder having a smooth cylindrical surface with a longitudinal slot extending from end to end to receive the ends of a flexible printing band encircling the cylinder, the said cylindrical surface having gage-locating holes near the ends of the cylinder and equally spaced from said slot, said cylindrical surface also having screw threaded holes spaced circumferentially from said gage-locating holes, of a gage device for removable attachment to the cylinder and comprising a gage rod disposed longitudinally of the cylinder, standards for supporting said rod parallel with the axis of the cylinder, said standards having elongated bases extending circumferentially of the cylinder with bottom faces longitudinally curved to conform to and contact with said cylindrical surface, locating pins projecting from said bottom faces adjacent one of the ends of said bases and disposed in said gage-locating holes, the other ends of said bases having holes to register with said screw threaded holes, headed screws in said registering holes to fasten said standards to the cylinder, a slide movable lengthwise of said rod, means for fixing said slide in an adjusted position on said rod, a vertically disposed gage plate fixed to said slide and having its lower edge curved to conform to the curvature of the cylinder and to coact with a printing band thereon, a gage bar disposed longitudinally of the cylinder and having a straight edge to coact with a printing band thereon, and a pair of suspending arms for said bar pivotally hung from said rod and disposed for contact with the opposite faces of said standards to prevent longitudinal movement of said bar, the lower portion of said gage plate being cut away to clear the rod and bar.

EDWARD LEEBERG.
